DESIGN FOR A FLATIRON CRADLE

Nikolai N. Skaredoff, New York, N. Y.

Application October 19, 1946, Serial No. 134,100

Term of patent 7 years

(Cl. D49—6)

To all whom it may concern:

Be it known that I, Nikolai N. Skaredoff, a citizen of the United States, residing at 116 Seaman Ave., New York 34, in the county of New York and the State of New York, have invented a new, original, and ornamental Design for Flatiron Cradle, of which the following is the specification, reference being had to the accompanying drawing, forming part thereof.

Figure 1 is a perspective view of a flatiron cradle showing my new design; Figure 2 is a top plan view thereof; and Figure 3 is a side elevational view thereof.

I claim:

The ornamental design for a flatiron cradle, substantially as shown.

NIKOLAI N. SKAREDOFF.
